SAFETY MATCH BOOK

William C. Thomas, Fries, Va.

Application April 2, 1938, Serial No. 199,715

7 Claims. (Cl. 206—29)

This invention relates to packaged safety matches designed for pocket use and pertains particularly to an improved safety match book.

As is, of course, well known, it frequently happens that with the use of safety matches put up in the form of a flat package or book, particularly painful accidents occur when the user of the match book strikes a match on the striking surface provided at the base of the match group. 5 without first closing the protecting flap which is provided to cover the heads of the group of matches remaining in the book. Various means have previously been devised for preventing such accidents but none has been satisfactory in view 10 of the fact that in all cases it is possible to strike the match while the heads of the matches remaining in the book are exposed, if the user of the match book is disinclined to use the book as it is supposed to be used.

20 The present invention has for its primary object to provide a safety match book wherein the striking surface provided for igniting a match is covered so long as the protecting flap of the book is open so that it is necessary for the user 25 of the book, in order to expose the striking surface, to first close the flap over the matches remaining in the book.

Another object of the invention is to provide a safety match book of the above described character which is of relatively simple construction and which may be easily stamped out with forming dies and have the parts of the book secured together in working relation by the use of only three of the ordinary wire staples which are used 35 for securing together articles of this character.

Still another object of the invention is to provide a safety match book of the above described character wherein the matches may be provided in the usual two row group to be secured at the 40 base of the group in the usual manner between a back and edge flap of a cardboard holder which is formed in the usual manner to have one end folded over the heads of the matches and engage behind the base flap so as to close the book.

45 The invention will be best understood from a consideration of the following detailed description taken in connection with the accompanying drawing forming part of this specification, with the understanding, however, that the invention is not to be confined to any strict conformity with the showing of the drawing but may be changed or modified so long as such changes or modifications mark no material departure from the salient features of the invention as expressed 50 in the appended claims.

In the drawing:

Figure 1 is a view in perspective of the device embodying the present invention.

Figure 2 is a longitudinal section through the match packet with the match cover flap opened. 5

Figure 3 is a section similar to Figure 2 showing the flap closed.

Figure 4 is a view of the blank from which the cover is formed.

Figure 5 is a view of the slide strip per se, with 10 the elastic attached.

Figure 6 is a section on the line 6—6 of Figure 1.

Referring now more particularly to the drawing, the numeral 1 generally designates the cardboard strip which is employed to provide the carrier for the group of matches, here indicated generally by the numeral 2, and shown as comprising the usual two rows of cardboard matches which are disposed one in front of the other to 20 be secured together at their bases, in the manner hereinafter described. The cardboard strip 1, forming in the body of the match book, is designed to be folded transversely intermediate its ends along the line 3 so as to form the back portion 4 and the front portion or cover flap 5 between which two portions the match group is housed. 25

In carrying out the present invention, a portion of the free end of the body 1 is turned back 30 to form the bottom flap 6 which is relatively wide and which has the transverse window opening 7 formed therethrough. This window opening is formed so as to leave a relatively wide portion between it and the free end edge of the flap, as 35 indicated at 8, which portion constitutes a cover means for the match scratch or abrasive surface hereinafter described.

The bottom ends of the matches of the match group are disposed in the assembled book to lie 40 between the panel-like end portion 8 of the flap 6 and the back 4 with the bottom edge of the match group substantially in the line of the top edge of the window opening 7 and there are disposed across both side faces of the match group 45 at the lower end of the matches and at each side of the match group, the spacer strips 9 which maintain a part of the match group at the front and at the back thereof in spaced relation with the panel 8 and the back 4 and the usual wire 50 securing staples 10 are ther passed through the parts 4 and 6 and the spacer strips 9 and interposed portions of the match group so as to secure these parts in assembled relation.

Prior to the application of the securing staples 55

- 10, there is folded across the lower edge of the match group 2, one end of a sliding strip 11. This said end of the sliding strip 11 is made slightly wider than the remaining portion of the strip, as indicated at 12, and is provided upon one face with the abrasive material 13 which must be employed in association with safety matches in order to effect their ignition and the abrasive carrying part 12 of the sliding strip 11 is positioned between the front spacer strips 9 and in the area between the lower part of the match group 2 and the panel 8. This area is indicated by the numeral 14. The other part of the strip 11 lies at the back of the match group in the area between the group and the back wall 4 of the book and between the back spacer strips 9 and extends upwardly behind the match group as shown. Secured to the back 4 in spaced relation with the free end of the sliding strip 11 is 15 a means for attaching a resilient band 15 to the back 4 of the book, which band is secured in any suitable manner to the adjacent end of the sliding strip 11 as, for example, by engaging it in notches 16 formed in the edges of the strip 11 and the securing means here shown for the band 15 comprises a small square 17 of cardboard or other suitable material which is secured to the back 4 of the book by a wire securing staple 18. It will, of course, be readily apparent that any 20 other suitable means may be employed for attaching the elastic band 15 to the back of the book and also for connecting the band with the adjacent end of the sliding strip 11, therefore, while this particular securing means, together 25 with the other parts described, is considered to be novel, it is to be understood that the invention is not to be restricted to the specific means illustrated and described for connecting these parts together.
- 30 40 The free end of the flap portion 5 of the book is formed to provide a tongue 19 which is of the proper width to be inserted between the upturned end portion 12 of the sliding strip and the bottom of the match group 2 so that the book flap 5 will be frictionally retained in covering relation with the group of matches.

In the use of the present device, after one of the matches has been removed in the usual manner, the flap 5 is turned down and the tongue 50 19 is inserted between the match group and the abrasive carrying flap portion 12 of the sliding strip 11. It will be seen, however, that the said abrasive carrying portion of the sliding strip will be hidden behind the protective panel 8 as the 55 elastic band 15 will constantly exert an upward pull upon the strip and as the lower end of the strip is folded over the lower edge of the match group, the abrasive carrying portion 12 will be pulled up until its further movement is stopped 60 by the secured match group. In order that the abrasive 13 may be exposed for use, the user of the book must exert longitudinal pressure against the flap 5 so that the tongue 19 will be forced downwardly against the folded lower part of the sliding strip 11 and this will effect the longitudinal movement of the sliding strip against the resistance of the resilient band 15 and will shift the abrasive carrying portion 12 into position where it will be exposed through the window opening 7. The match may then be drawn across the abrasive and ignited and as soon as the said longitudinal pressure against the flap 5 is released, the resilient band 15 will react to pull the exposed abrasive back into shielded position behind the panel 8.

From the foregoing it will be readily apparent that unless the entire match book is torn apart, it is impossible for the user to strike a match while the cover flap of the book is raised and the heads of the remaining matches are exposed. In other words, the user is compelled to replace the flap into the usual shielding or covering position before he can obtain the abrasive material in a position for striking the match and thus the user will be protected against accident in spite of any inclination to use the match book carelessly.

I claim:—

1. A match package comprising, a group of matches adapted to be separated for individual use, an abrasive striking panel shiftably attached to the match group at the base of the same, a shield panel for said abrasive panel, resilient means normally maintaining the abrasive panel behind the shield panel, a carrier for the match group, and a shield flap forming a part of the carrier and adapted when in shielding relation with the match group to effect the shifting of the abrasive panel relative to the shield panel.

2. A match package comprising a match group in which the matches are adapted to be separated for individual use, a carrying body to which the match group is secured, means forming a covering for the secured end of the match group and having a window opening, an abrasive carrying panel slidably between said last means and the match group for exposure through said window opening and normally shielded by a portion of said last means, resilient means normally urging said sliding panel into shielded position, and a cover flap connected with the carried body and adapted to overlie the match group, and means forming a part of the cover flap for effecting the shifting of said panel into the window opening.

3. A match book, comprising a group of joined matches adapted to be separated for individual use, a carrying envelope for said group comprising a foldable strip of material having the portion of one end folded back upon itself to form a securing flap between which flap and the adjacent portion of the strip the bottom of said match group is secured, a portion forming a cover flap the free end of which is adapted to frictionally engage between the securing flap and the match group, said securing flap having a window opening therein and a panel portion between the opening and its adjacent end edge of the securing flap, an abrasive carrying body slidably positioned between said panel and the match group and adapted when shifted in one direction to be exposed through said opening, resilient means normally retaining said body behind said panel, and said cover flap having its free edge adapted for use in shifting said body into position for exposure through said opening.

4. A safety match book, comprising a group of matches secured together at one end and adapted to be separated for individual use, a carrier for said group comprising an elongated strip of material having a portion of one end folded back to provide a securing flap beneath which the said end of the match group is secured, a portion of the strip at the other end constituting a cover flap to be folded over the match group, said securing flap having a window opening formed therein and having a portion providing a covering panel, an elongated strip of material slidably positioned between the match group and the strip of material to which it is

- secured, said sliding strip having an end turned up across the end edge of the match group to provide a portion which is covered by said panel, an abrasive striking material on the said turned portion of the sliding strip and adapted for exposure through said opening when the strip is shifted in one direction, resilient means normally urging the movement of said sliding strip to a position where the abrasive material is covered by said panel, said resilient means connecting the sliding strip with the first mentioned strip, and a tongue forming a part of said cover flap and insertable between the panel and the match group and adapted to effect the shifting of the sliding strip for the exposure of the abrasive material through said opening.
5. A match package, comprising a group of matches separable for individual use, an abrasive striking panel disposed across the match group adjacent the base thereof and slidable in a plane parallel therewith, shield means secured to the match group behind which the panel may be positioned, and a cover for the match group having a free edge insertible between the shield means and said base when in covering relation with the matches for engagement with the said panel to shift the panel from behind the shield.
6. A match package, comprising a group of matches joined together by a base portion from which they may be individually separated, means secured to said base portion forming an enclosed area therebeneath and including a shield panel spaced from the base portion, an abrasive strik-
- ing panel slidably disposed between said base and said shield panel for movement downward into said area, the striking panel when moved into said area being exposed for use, a cover flap for the matches connected with said means and having a free edge insertible between the base and shield panel, and means engageable by said cover panel edge when in match covering position whereby movement of said edge in one direction will effect the uncovering of said striking panel.
7. A match package, comprising a group of matches joined together by a base portion from which they may be individually separated, means secured to said base portion forming an enclosed area therebeneath and including a shield panel spaced from the base portion, an abrasive striking panel slidably disposed between said base and said shield panel for movement downward into said area, the striking panel when moved into said area being exposed for use, a cover flap for the matches connected with said means and having a free edge insertible between the base and shield panel, means engageable by said cover panel edge when in match covering position whereby movement of said edge in one direction will effect the uncovering of said striking panel, resilient means normally urging said striking panel to move between the shield panel and said base, and said flap edge engaging means limiting the movement of the striking panel under the urge of said resilient means through contact with said match base.
